UNITED STATES PATENT OFFICE.

JAMES A. BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

MACHINE FOR LAYING SOLES.

1,146,303.

Specification of Letters Patent. Patented July 13, 1915.

Application filed April 20, 1911. Serial No. 622,209.

To all whom it may concern:

Be it known that I, JAMES A. BROGAN, a citizen of the United States, residing at Lawrence, in the county of Essex and State 5 of Massachusetts, have invented certain new and useful Improvements in Machines for Laying Soles; and I do hereby declare the following to be a full, clear, and exact description of the invention, such as will enable others skilled in the art to which it 10 pertains to make and use the same.

The present invention relates to sole laying machines.

Heretofore it has been the practice in laying soles, after cement has been applied to one or both of the engaging surfaces of sole and shoe and the sole has been properly positioned upon the shoe, to apply pressure to the sole simultaneously throughout substantially its entire surface, and the machines of the prior art have operated in accordance with the above described process. Inasmuch as the wooden lasts upon which the shoes are supported during the laying 25 operation are obliged to sustain at one and the same time the total pressure applied to the entire sole, these lasts are liable to be broken or otherwise damaged. As a result the pressure per unit area which may be applied to the various portions of the sole is limited and difficulty is experienced in properly laying the sole, particularly in the shank.

One of the objects of the present invention is to produce a machine for laying soles in which a high pressure per unit area may be employed yet without danger of damaging the lasts. This object is accomplished, generally speaking, by applying the pressure 35 to first one portion of the sole and then to another, the total pressure applied at any one time never exceeding the strength of the lasts. Preferably this pressure is applied by a rocking or rolling form or pressing 45 member which operates progressively along the length of the sole, this method or mode of operation having the further advantage of spreading the cement and forcing out any surplus cement or air bubbles.

Another object of the present invention is to produce a machine for laying soles in which the sole is held in proper position on the shoe while pressure is being applied and this is accomplished by holding or clamping

one portion of the sole against the shoe while pressure is being applied at another portion.

Other objects and features of the invention will be set forth in connection with the following description of the illustrated embodiment of the invention.

In the accompanying drawings Figure 1 is a side-elevation of a sole-laying machine embodying the present invention; Fig. 2 is a side-elevation, on a larger scale, showing particularly the jack and toe-clamp, with the 60 toe-clamp in operative position; Fig. 3 is a side-elevation on a still larger scale, showing the toe-clamp and its actuating mechanism in operative position; Fig. 4 is a similar view showing the toe-clamp in inoperative position; Fig. 5 is a front-elevation of the jack and the toe-clamp mechanism; Fig. 6 is a side-elevation of the toe-clamp lever; Fig. 7 is a detail plan-view of the trip for the toe-clamp mechanism and Fig. 8 is a 65 front elevation, and Fig. 9 a side elevation, of the trip lever for actuating the toe 70 clamp lever, with a portion of the handle broken off.

I employ a machine having an adjustable 80 jack upon which lasts of various sizes and styles may be supported, and a sole-pressing form so shaped as to engage the work progressively. Any suitable mechanism may be employed for relatively actuating the form 85 and jack, that illustrated in the drawings being similar to the mechanism disclosed in the patent to Benjamin F. Mayo, No. 861,746, dated July 30, 1907. Such mechanism is not, therefore, fully described in this application but is illustrated only in so far as is necessary for an understanding of the operation of the machine.

The present machine, like that of the patent referred to, is a twin or double machine, 95 having duplicate parts so that while one shoe is being subjected to the laying operation by one set of instrumentalities, the other set of instrumentalities are in a position of presentation, that is to say, a position 100 in which the operator may remove and replace the work. In the drawings, however, only one set of instrumentalities is illustrated, namely, those at the right-hand side of the machine.

As shown in Fig. 1, the form is carried by a swinging arm 11 which is pivoted at 105 12 upon the frame 13 of the machine. The

jack is carried by an arm 14, which is pivoted at 15, on the frame of the machine. The arm 14 is oscillated about its pivotal support by means of a link or connecting rod 16, of which the upper end is pivoted to the arm while the lower end engages a crank 17 on a crank-shaft 18. The arm 11 is oscillated simultaneously with the arm 14, by means of a link 20 which is pivoted at its lower end to the arm 14, and at its upper end to an arm 30 projecting forwardly and integral with the arm 11.

Upon the crank-shaft 18 is fixed a gear 19, which is rotated by a worm 21. The worm is carried by a power-shaft 22 journaled in the frame of the machine. Upon the power-shaft a pulley 23 is loosely mounted, the pulley being movable both rotatively and longitudinally on the shaft. This pulley is constantly rotated by a belt (not shown) connecting it with any suitable source of power.

When the machine is out of operation the pulley rotates freely, but it may be operatively connected with the power-shaft by means of a clutch comprising a conical member 24 fixed to the shaft, coöperating with a corresponding recess in the pulley. The pulley is provided with an annular groove 25 on its hub, which is engaged by the forked upper extremity of a shipper-lever 26, and by these means the pulley may be moved into engagement with the clutch-member 24. The lever 26 is fixed to a rock-shaft 27, which is provided also with an arm 28 connected by means of a link 29 with a lever 31. The lever 31 is fixed on a rock-shaft 32, and is provided with a roller 33 engaging a cam 34. The cam is fixed on a rock-shaft 35 provided at its forward end with a treadle 36. When the treadle is depressed by the operator the cam raises the lever 31 and through the connections described throws the clutch into operation so as to rotate the power-shaft and actuate the jack and the form.

The rock-shaft 32 is provided with an arm 37 having a cam-roll 38 engaging a cam 39 on the crank-shaft 18. When the treadle is raised by the operator to stop the machine a spring 41 connected with the arm 37 tends to raise the arm, and a spring 42, connected with the shipper-lever, tends also to move the latter to the left and disengage the clutch-members. The cam 39 acts, however, to prevent such disengagement until the mechanism has moved to a position in which the jack and the form are in their forward inoperative position or position of presentation. When this position is reached, the cam-roll 38 is free to enter a depression on the cam-surface and the mechanism then comes to rest. A brake 43 is connected with the clutch-mechanism and is adapted to engage a brake-disk 44 on the power-shaft

when the clutch is disengaged so as to arrest the machine immediately.

The sole-pressing form 45 consists preferably of rubber or other yielding material and is shaped to conform transversely to the required shape of the sole. The form is shaped longitudinally to engage the sole progressively as the jack and form are rocked. The form is removably secured in a carrier or bed 46 which is pivoted at 47 to a head fixed at the lower end of a stem 49. The stem 49 slides in a socket in the arm 11, and is pressed downwardly by a spring 50, shown in dotted lines in Fig. 1. The downward movement of the stem is limited by a stop-screw 51 threaded into the head 48 and engaging a lug 52 on the arm 11. The bed 46 may be adjusted about its pivotal support by means of two screws 53 threaded into the head 48 and engaging the bed.

The construction of the jack is illustrated particularly in Fig. 2. It comprises a base-member 54, mounted upon a stem 55 which is seated in a socket in the arm 14. The stem is normally fixed in the socket by a set screw 56, but it may be adjusted vertically therein by means of a screw 57 engaging the lower end of the stem.

The jack is provided with a heel-post 58, upon the upper end of which is pivoted the usual heel-pin 59 adapted to enter the socket in the heel of the last. The heel-pin is pivoted, at 61, on the heel-post, and a spring 62 acts normally to tilt the heel-pin forward so as to press the toe of the last against the toe rest.

The heel-post is adjustable on the base 54, according to the length of the last to be supported, and to this end it is provided at its lower end with flanges 63 embracing a guide 64 on the base.

The toe-post 65 carries at its upper end the toe rest 66. The toe rest is supported by a universal joint in order that it may conform to the various shapes and sizes of lasts employed. To this end the toe-rest is provided with a lug 67 pivoted in a yoke 68, and the yoke is pivoted, in turn, between lugs 69 at the upper end of the post. The toe-rest is normally retained in upright position by means of a plunger 72, see Fig. 4, which slides in a socket in the toe-post and engages a flat surface 71 on the bottom of the yoke 68. This plunger is pressed upward by a spring 73 shown in dotted lines in Fig. 4. The toe-post is mounted adjustably on a guide 70 on the base-member 54.

A lasted shoe 75 is mounted upon the jack as shown in Fig. 2, and the heel-post and toe-post are moved toward and from each other to accommodate them to the length of last. In changing from one size of last to another it is not necessary, in all cases, to change the form employed in connection

with the last, provided the position of the shank of the last is adjusted to coincide with the corresponding portion of the form. For this reason means are provided by which 5 the heel-post and toe-post are always adjusted simultaneously in opposite directions and through proportionate distances. As shown in Fig. 2, the toe-rest is connected, by a link, 76 to the upper end of a lever 77, which is pivoted at 78 on the base-member 54 of the jack, and the lower end of the lever 77 is connected by a link 79, with the heel-post. To permit a greater range of 10 adjustment, extra holes 81 are provided in position to receive the screws 90 by which the links are pivoted to the posts.

To fix the posts in adjusted position, I employ a latch illustrated particularly in Figs. 3, 4, and 5. The upper surface of the 20 guide 70 is provided with rack-teeth 80, which are engaged by a tooth at the lower end of a latch 82. The latch slides in a recess in the toe-post and is pressed down by a spring 83. The latch has an upwardly 25 projecting stem 84, which is notched at its upper end to receive a pin 85 projecting from a lever 86. The lever 86 is pivoted at 87 on the toe-post and it has an upward extension 88 constituting a handle by which 30 the lever may be swung to disengage the latch from the teeth 80 when the jack is to be adjusted.

To hold the heel-end of the sole in position on the shoe during the operation of the 35 form on the other parts of the sole, the present machine is provided with a heel-clamp 89 mounted on an arm 91 which is constructed and operated the same as in the case of the heel-clamp of the Mayo patent hereinbefore referred to and further description 40 of this part is not, therefore, necessary herein. To hold the toe-end of the sole in a similar manner, the present machine is provided with a toe-clamp of novel construction 45 and operation. This toe-clamp comprises a bifurcated finger 92 having a slotted shank which is adjustably secured by screws 93 to a lever 94. This lever, as shown in Figs. 3, 4, and 6, has an elongated opening 95 and is secured to the toe-post 65 by a screw 96 passing through the opening 95. This connection is such as to permit both 50 pivotal and longitudinal movements of the toe-clamp lever on the heel-post.

55 The movements of the toe-clamp lever are controlled by a trip lever having a hub 97 journaled on the screw 96 outside of the toe clamp lever. The toe-clamp lever is provided at its lower end, with a sleeve 98 in 60 which is a coiled compression spring 99 engaging the hub 97 of the trip lever. This spring tends constantly to pull the toe-clamp lever downward until the upper end of the opening 95 engages the screw 96.

65 In the inoperative position of the ma-

chine the toe-clamp is held in raised position against the action of the spring 99 by means of a cam projection 101 on the trip lever. This cam engages a lug 102 on the toe-clamp lever, as shown in Fig. 4, and 70 thus holds the lever in raised position with the finger 92 in the position shown in Fig. 4. When the lasted shoe has been placed upon the jack by the operator, the operator pulls forward an arm 103 constituting 75 part of the trip-lever, thus rocking the cam 101, and the toe-clamp lever rocks with the trip-lever until the finger 92 extends over the end of the sole 100 which has been laid loosely upon the lasted shoe. When the toe-clamp reaches this position, the swinging movement of the toe-clamp lever is arrested by means of an adjustable stop-screw 107 which is threaded in the lug 102 and which 80 engages a lug 108 on the toe-post. The continued forward movement of the arm 103 then rocks the cam 101 out of engagement with the lug 102, whereupon the spring 99 pulls the toe-clamp lever and the toe-clamp 85 downward, thus causing the finger 92 to 90 press downward upon the sole.

With the parts in the position just described, the machine is thrown into operation and the jack and the form swing rearwardly into operative position. The engagement of the work occurs first at the heel portion of the sole, and the pressure is then transferred by a continued rolling motion toward the toe of the sole. As soon as the heel portion has been disengaged by 100 the form, the heel clamp 89 moves into engagement with the heel-end of the sole. As the form approaches the toe-end of the sole, it is necessary to remove the toe-clamp 105 therefrom, and this operation is performed automatically. A trip-finger 109, shown in Figs. 1, 2 and 7, is fixed adjustably by means of a set screw 111 in a lug 112 mounted at the inside of one of the uprights constituting a portion of the frame 13 of the 110 machine. As the jack swings rearwardly, this trip-finger engages an arm 113, which constitutes a portion of the trip-lever and projects upwardly from the hub 97 in the position shown in Figs. 1 and 2. By the engagement of these parts the arm 113 is 115 swung forward during the continued movement of the jack, thereby bringing the cam 101 again into engagement with the lug 102 on the toe-clamp lever. The toe-clamp lever is thus swung forwardly so as to disengage the finger 92 from the sole, and when it has swung to the position of Fig. 4, a stop-screw 104 on the lever engages a lug 120 105 on the toe-post. The swinging movement is thus arrested and the continued movement of the cam 101 causes the lug 102 to ride upon the cam, thus raising the toe-clamp lever into its inoperative position as 125 in Fig. 4.

The movements of the trip-lever are limited in both directions by means of a stop 106 fixed to the toe post and engaged alternately by the arm 103 and the cam 101.

5 During the forward or return movement of the jack the pressure of the form is transferred progressively from the toe to the heel of the sole. The rocking movements are 10 repeated until the operator depresses the treadle to set in operation the second or companion mechanism, when the first set of devices comes to rest with the parts in their forward position of presentation, and with the toe-clamp ready to be moved into 15 engagement with the next sole by the operation of the arm 103.

It will be understood that my novel sole-laying machine is not limited to the details 20 of construction and operation of the illustrated embodiment thereof, but may be embodied in various other forms within the nature of the invention, as it is defined in the following claims.

I claim:

25 1. A sole laying machine, having, in combination, a shoe supporting jack, a pressing form for laying a sole upon the shoe, mechanism for relatively actuating the jack and form to apply pressure progressively to the sole, a plurality of clamps engaging with the sole at different points, and mechanism 30 acting automatically for removing each of the clamps from the sole prior to the contact of the form with that portion of the sole engaged by the clamp.

2. A sole laying machine, having, in combination, a jack for supporting the shoe, a form, means for imparting relative rocking movement to the jack and form to apply 40 pressure to the sole progressively along the same from the heel to the toe, a toe clamp for holding the toe portion of the sole against the shoe while pressure is being applied to the heel and shank portions of the sole, a heel clamp for holding the heel portion of the sole against the shoe while pressure is being applied to the toe portion of the sole, and automatic mechanism for withdrawing the toe clamp before pressure is applied to the toe portion of the sole, substantially as described.

3. A sole laying machine, having, in combination, a jack for supporting the shoe, a form, mechanism for relatively actuating the form and jack to apply pressure to the sole progressively from heel to toe and back to the heel again, a toe clamp for holding

the toe portion of the sole against the shoe, 60 automatic mechanism for withdrawing the toe clamp from the sole before pressure is applied to that portion thereof, a heel clamp for holding the heel portion of the sole against the shoe, and automatic mechanism 65 for applying the heel clamp after pressure has been applied to the heel and for withdrawing the heel clamp before pressure is applied again thereto, substantially as described. 70

4. A sole laying machine, having, in combination, a jack for supporting the shoe, a form, mechanism for relatively actuating the jack and form to apply pressure to the sole, a toe clamp for holding the toe of the 75 sole against the shoe, a spring pressed support for the toe clamp, a knock-off lever for throwing the toe clamp out of engagement with the sole, and means for actuating the knock-off lever, substantially as described. 80

5. A sole laying machine, having, in combination, a jack for supporting the shoe, form supporting means, a form pivoted thereon, means for adjusting the form about its pivotal support and for rigidly maintaining the form in any adjusted position, and mechanism for relatively actuating the form and jack to apply pressure to the sole 85 progressively along the same, substantially as described. 90

6. A sole laying machine, having in combination, a jack for supporting the shoe, a form, mechanism for relatively actuating the jack and form to apply pressure to the sole progressively along the same, a toe 95 clamp arranged to engage the sole and hold the toe of the sole in position against the shoe while pressure is being applied to another portion of the sole, and automatic mechanism for withdrawing the toe clamp 100 before pressure is applied to the toe portion of the sole, substantially as described.

7. A sole laying machine, having, in combination, a jack for supporting the shoe, a form, mechanism for relatively actuating 105 the jack and form to apply pressure to the sole progressively along the same, and means for engaging the sole and holding the sole in position during the sole laying operation whereby one portion of the sole is 110 held from displacement with relation to the shoe while pressure is being applied to another portion of the sole, substantially as described.
